JOHN T. STONEY AND KLEMENS PURWIN, OF CLEVELAND, OHIO, ASSIGNEES TO THE STONEY FOUNDRY ENGINEERING AND EQUIPMENT CO., OF CLEVELAND, OHIO, A CORPORATION OF OHIO.

APPARATUS FOR VIBRATING OBJECTS.

Application filed September 12, 1921. Serial No. 500,193.

Our invention relates to means for vibrating objects for the purpose of removal of sand, dirt, or other matter adhering to boxes, foundry flasks, and the like.

5 The object of our invention is an efficient means for vibrating objects for quickly and thoroughly loosening and removing sand, dirt, or other matter which adheres to boxes, foundry flasks, and the like.

10 In foundry flasks for instance, it is customary to loosen the sand, which adheres to the walls of the flasks after a mold is cast, by manual pounding on the flask with a mallet or other instrument to create vibrations in 15 the material of the flask and thereby loosen this sand. The vibrations so created, however, are not sufficiently sharp to remove or eject this loosened sand from the flask and it is necessary to scrape or otherwise remove 20 this loosened sand from the flask.

Such procedure not only consumes time and labor, but also causes the flasks to be broken quite frequently by careless workmen.

To overcome these objections, the present 25 invention provides an apparatus whereby vibrations are created in the object to be cleaned, which vibrations are sufficiently sharp and rapid to not only loosen but also remove or eject the adherent matter, thereby reducing the time required to vibrate the 30 object and eliminating the time required for scraping and cleaning. With the present invention, in most cases, this cleaning or ejecting is done, or can be done by having the 35 vibrators working while the object is being raised or otherwise suspended, thereby further saving time.

A mechanism to accomplish the above is 40 illustrated in the accompanying drawing as an exemplification and the apparatus so shown will be described in detail in this specification.

Various changes and modifications may be 45 made in the apparatus without departing from the spirit of this invention and without sacrificing any of the advantages contained in the appended claims.

In the accompanying drawing, Fig. 1 is a 50 general perspective view of a hook mechanism provided with means for engaging a foundry flask and with means for creating vibrations therein; Fig. 2 is a section on line 2 of Fig. 4; Fig. 3 is a section on line 3 of Fig. 4; Fig. 4 is a central longitudinal sec-

tion, on a larger scale, of the vibrator mechanism; and Fig. 5 is a partial view showing a modification of the hook legs and vibrator mounting.

Similar reference characters refer to similar parts throughout the views.

The apparatus shown in the drawing consists, mainly, of the hook mechanism A, and the vibrators B, supporting the foundry flask C.

The hook mechanism A has the bale 10 to 65 which the loop 11 is secured, and also has the legs 12 each of which has the opening 13, preferably rounded at the top as shown, to permit the legs to rock on the bale upon which the legs are suspended, and also has the lugs 70 14 and 15 and the hook end 16.

These legs are suspended from the bale by the openings 13 therein as shown and are held in position thereon by the pins 17 spaced some 75 distance from the legs to permit the same to rock on the bale.

The vibrators B, presently described in detail, abut firmly against the lugs 14 and are held to the legs by the screws 18.

The taper keys 19 are interposed between 80 the bottom of the vibrators and the lugs 15 and are adapted to be adjusted to take up wear or lost motion and are locked in adjusted position by the nuts 20.

The plates 21 hook over the lugs 14 and 15 85 and are provided to re-inforce the legs 12 at the point where the vibrations are created and also to hold the keys 19 in position sideways.

The pipe 22 with the valve 23 and the inlet 90 pipe 24 is secured to the bale by the clips 25 and preferably has a hose connection with the source of fluid pressure and also has the hose portions 26 for connection to the vibrator inlet pipes 28.

A vibrator, well adapted to the hook shown, is shown on a larger scale in Figs. 2, 3, and 4, consists of the cylinder 29 which is provided with a main bore, open at the bottom and terminating into the opening 30 at the 100 top. This cylinder also has the inlet opening 31, open at the top only and threaded there for the inlet pipe 28, and also has the inlet ports 32 and 33 opening into the opening 31. This cylinder also has two sets of 105 exhaust ports 34 and 35, each set consisting of eight holes. This cylinder also has threaded openings on one side for the screws 18.

and in the bottom for the screws 36 which hold the cap 37 on the cylinder.

Inside of the main bore of the cylinder is the sleeve 38 which is provided with inlet and exhaust ports corresponding to the ports 32, 33, 34, and 35.

The anvil block 39 is driven into the opening 30 and has the flange 40 to present a large bearing surface against the material of the cylinder and also has the anvil surface 41.

The cap 37 is, preferably, centered in the main bore of the cylinder by the projection 42 and has the outer flat surface 43 against which the key 19 rests and is held to the cylinder by the screws 36. This cap also has the central opening 45 into which the anvil block 46 is driven.

The anvil block 46 has the flange 47 to present a large bearing surface against the material of the cap, and also has the anvil surface 48.

The openings 30 and 45 permit of ready removal of the anvil blocks 39 and 46 when it is necessary to remove them for any purpose.

Inside of the sleeve 38 is the plunger 49 which has the anvil blocks 50 and 51, similar to the anvil blocks 39 and 46, driven into the ends thereof, and also has the grooves 52 and 53, and the port holes 54 and 55 between the grooves and the outer ends of the plunger, respectively, as shown.

The plunger is, preferably, hardened as a whole and the anvil blocks 39, 46, 50, and 51, and particularly the anvil surfaces thereof, should be as hard as possible to prevent upsetting, but should not be sufficiently brittle to chip or permit pieces to break off. The shank portion of all of the anvil blocks and particularly the juncture of the shank and the flange, which should be rounded, should be comparatively soft to prevent crystallization at that point.

The grooves 52 and 53, and the inlet ports 32 and 33, and the exhaust ports 34 and 35 should be so spaced that the groove 52 is opposite the exhaust ports 34 and the groove 53 is opposite the inlet port 33 when the plunger is in its lowest position as shown in Fig. 4, and so that the groove 52 is opposite the inlet port 32 and the groove 53 is opposite the exhaust ports 35 when the plunger is in its uppermost position.

The modification shown in Fig. 5 eliminates the plate 21 and the key 19 and the nut 20 but, in this instance, the vibrators B should be closely fitted endwise in the legs. If this is not done, the screws 18 will become loose after short use of the vibrator, thereby not only mitigating the effect of the vibrators, but also causing the screws 18 to crystallize.

The operation of the mechanism shown and described is as follows: The plunger being in its down position, due to its own weight when fluid pressure is shut off, as

shown in Fig. 4. Fluid pressure is now turned on by means of the valve 23 and flows into the pipe 22, through the hose portions 26, into the pipes 28, and into the openings 31. Both vibrators are now ready for action and will act independent of each other but the action of both are alike hence the operation of one vibrator only will be described.

The plunger being in its lowest position, the inlet port 33 registers with the groove 53 and fluid pressure now flows from the opening 31, into the port 33 and the groove 53, through the port hole 55, and into the space 56. The fluid pressure now forces the plunger upward until it strikes the anvil block 39, which action creates vibrations in the block 39 and these vibrations are transmitted to the cylinder 29 and to the legs and to the flask C which is suspended on the legs.

During this upward movement of the plunger, the groove 52 registers with the exhaust ports 34 and the fluid pressure now in the space 57 exhausts through the port holes 54, the groove 52, and the exhaust ports 34.

When the plunger reaches this upper position, the groove 52 registers with the inlet port 32 and the groove 53 registers with the exhaust ports 35. Fluid pressure now flows from the opening 31, into the port 32, into the groove 52, and through the port holes 54 into the space 57, and forces the plunger down until it strikes the anvil block 46, which action again creates vibrations which are transmitted to the cap 37, to the key 19, to the legs, and to the flask C.

During this downward movement of the plunger, the groove 53 registers with the exhaust ports 35 and the fluid pressure now in the space 56 exhausts through the port holes 55, the groove 53, and the exhaust ports 35.

This operation of the apparatus and both of the vibrators is repeated automatically and continues to repeat as long as fluid pressure is supplied.

It is noted that a series of exhaust ports are provided at each exhaust position of the cylinder for the purpose of complete and quick exhaustion, so that no resistance acts on the plunger and so that the plunger strikes the anvil blocks with full force and creates sharp vibrations.

It will further be seen that the apparatus of the present invention is efficient since there are few parts, the parts subject to wear are easily replaced, sharp and effective vibrations are created, and these vibrations are effectively transmitted to the object operated upon by metal to metal contact.

We claim:

1. An apparatus of the character described, comprising a hook mechanism having at least one leg to engage an object and an upper supporting structure, and means mounted upon said leg for creating vibrations therein.

2. An apparatus of the character described, comprising a hook mechanism having two legs, and a vibrator mechanism mounted in each of said legs. 25
- 5 3. An apparatus of the character described, comprising a hook mechanism having two legs, and a vibrator mechanism mounted in each of said legs and each end of each vibrator adapted to solidly abut the 10 material of one of said legs.
4. An apparatus of the character described, comprising a hook mechanism having two legs, and a vibrator mechanism mounted in each of said legs, and means for 15 holding each end of said vibrator mechanisms solidly against the material of said hook mechanism.
5. In an apparatus of the character described, the combination of a hook adapted 20 to engage an article to be operated upon, and a vibrator solidly held in said hook.
6. In an apparatus of the character described, the combination of a hook adapted to engage an article to be operated upon, and
- a vibrator mounted in said hook, and a wedge means between said vibrator and said hook to form a solid connection between said vibrator and the material of said hook. 25
7. In an apparatus of the character described, the combination of a hook member 30 having two legs adapted to engage an article to be operated upon, a vibrator mounted in each of said legs, and a wedge means between each of said vibrators and the corresponding of said legs to form a solid connection between each of said vibrators and the material of said corresponding legs. 35
8. In an apparatus of the character described, the combination of a hook member having two legs adapted to engage an article 40 to be operated upon, a vibrator mounted in each of said legs, a taper key between each of said vibrators and the corresponding of said legs, and means for adjusting and locking said key. 45
